EMBALMER'S HAND HOLDER

Howard Randolph Holt, North Smithfield, R.I.
(56 Smithfield Road, R.F.D. 2, Woonsocket, R.I.)
Filed Feb. 1, 1960, Ser. No. 6,015
3 Claims. (Cl. 27—21)

This invention relates to improvements in embalmer's hand holding devices.

At death and after rigor mortis, all body parts, muscles and other tissues assume a partly relaxed state or position. This condition, however, is not natural in appearance. The relatives of a deceased person desire the embalmer to prepare the corpse to have as natural an appearance as possible for sentimental reasons. Accordingly, it is the aim and desire of an embalmer to restore and maintain the position of the various parts of the body of the deceased to as natural a semblance as possible to please the members of the family of the deceased person.

One of the problems which embalmers encounter in preparing a body for burial is the arrangement of the hands which tend to fly apart and assume unnatural or grotesque positions. Also, even after the embalming process has been completed and the hands are clasped across the body of the deceased person with the elbows braced against the casket sides, slipping occurs.

It is, therefore, the primary object of this invention to provide a simple and inexpensive device for use by embalmers on corpses by means of which the hands of a deceased person may be clasped one over the other and firmly held in such position to assume a substantially normal life-like appearance during and subsequent to the embalming operation.

A further object is to provide a device of this character which is contractile and adapted to apply a steady pressure sufficient to hold the superposed hands of a corpse in a firmly clasped position across the front of the body while at the same time applying pressure in an amount and in a manner so as to minimize distortion of the tissues.

Another object is to provide a device of this character of simple unitary construction which is easy to apply and will be capable of universal use in that it will accommodate various differences in sizes and shape and other properties of the fingers and thumbs of deceased persons.

A still further object of the invention is to provide a corpse hand holding device which will be concealed from public view during use on the corpse in a casket and thus is not removed from the deceased body at any time, even at interment.

Further objects and advantages are set forth in the following specification which describes a preferred form of the device as illustrated by the accompanying drawing:

In the drawing:

FIG. 1 is a pictorial view showing the novel device of this invention applied to a hand;

FIG. 2 is a pictorial showing of the corpse hand holding device, as viewed from the under side, in position on the clasped hands of the corpse after it has been embalmed;

FIG. 3 is a pictorial view of the FIG. 1 form of corpse hand holding device of the invention;

FIG. 4 is a top plan view of the corpse hand holding device shown in FIG. 3;

FIG. 5 is a vertical section in elevation taken on the line 5—5 of FIG. 4; and

FIG. 6 shows a modified form of the invention in which the device comprises two connected pieces.

Referring now in detail to the drawings, and in particular to FIG. 3 thereof, the corpse hand holder device of the present invention is generally designated by the reference numeral 10 and is made entirely of a suitable

2

resilient material, such as, for example, elastic rubber. The main body 12 of the device is of generally tubular formation of narrow width and constitutes a stretchable annular band which is susceptible to enlargement and contraction and which includes an integral projecting tab portion 14 having the same resilient properties and provided with a central opening 15 therethrough to form a holding loop for a thumb, as will be hereinafter described. The opening 15 may be of appropriate shape as, for example, circular or elliptical, and is of a size to accommodate and hold firmly a wide range of sizes and shapes of thumbs to be held therein.

In the use of the device, the arms of the deceased person are folded across the front of the body with the hands placed in a natural clasped position (not shown). Either the right or the left hand may rest on the other, as desired. As shown in FIGS. 1 and 2, the band portion 12 of the device 10 is expanded and placed around the proximal position of the first phalanx of the thumb 16 and the first phalanx of the forefinger 17 of the right hand 18 with the projecting tab portion 14 of the device extended under and toward the palm of the hand 18. The fingers of the left hand 19 are clasped over the fingers of the right hand 18 with the left thumb 20 inserted between the band 12 and the right hand 18 and through the opening 15 in the tab portion 14 of the hand holding device 10 which then is allowed to contract thus holding both hands securely in this desired arranged position (see FIG. 2).

If the right hand is to be placed in the upper position the foregoing described arrangement is reversed, in which case the band portion 12 of the device 10 is expanded and placed around the proximal position of the first phalanx of the thumb 20 and forefinger 21 of the left hand 19 with the projecting tab portion 14 extended under and toward the palm of that hand. The fingers of the right hand 18 are clasped over the fingers of the left hand 19 with the right thumb 16 inserted between the band 12 and the left hand 19 and through the opening 15 in the tab portion 14 of the hand holding device 10 which then is allowed to contract thus holding both hands securely in this desired arranged position.

The inside surface of the band or body portion 12 may be either smooth, or suitably roughened, as desired, in order to increase its gripping qualities.

Also, it is obvious that the band member 12 and the tab portion 14 may constitute separate pieces of resilient material which are adhesively joined together, as indicated at 25, and such modified form of the device 10 is considered to come within the scope of the instant invention, see FIG. 6.

It thus will be apparent that by means of this novel one-piece, simple and inexpensive device, with its resilient properties, the hands 18 and 19 will be held indefinitely in a relaxed clasped position, and that, as shown in FIG. 2, the device 10 is entirely concealed at all times from public view by virtue of its disposition on the underside of the clasped hands and therefore does not require removal from the body at any time.

Since it is obvious that many other changes and modifications of the above-described details can be made without departing from the nature and spirit of the invention, it is to be understood that the invention is not to be limited to the above-described details except as set forth in the appended claims.

What is claimed is:

1. An embalmer's hand holder device to support the hands of a corpse in clasped position across the front of the body comprising a resilient band member for encirclement of the thumb and forefinger of one hand of the corpse, and a resilient projecting tab portion integral therewith and extending well beyond and to one side of said

band member, said tab portion having a central opening therein which is of a size such as to accommodate therethrough, encircle, and hold firmly the extended thumb of the superposed hand following its projection from between the thumb and forefinger to be resiliently held by said band member.

2. An embalmer's hand holder device as claimed in claim 1 in which the resilient material is elastic rubber.

3. An embalmer's hand holding device of unitary construction adapted to support the superposed hands of a 10 corpse in natural clasped position of repose across the front of the body, comprising a resilient tubular body portion of narrow width and a resilient projecting tab portion integral with one side wall of said body portion and extending well beyond the same, said tab portion being provided with a central opening smaller than the size of a thumb joint, said tubular body portion forming

a band which is susceptible to enlargement and contraction for encircling disposition around the thumb and forefinger of one hand of the corpse, and said resilient tab portion being susceptible to enlargement and contraction for insertion of the thumb of the other hand through said central opening in said tab portion of the hand holding device following projection of the inserted thumb from between the first thumb and forefinger to be resiliently held by said tubular band, said device on contraction after placement exerting a firm and steady pressure on the engaged finger and thumb parts of the superposed hands to hold them in the desired arranged position.
